UNITED STATES PATENT OFFICE.

ALMOND J. WHITE AND FREDERIC A. HAWLEY, OF CHILlicothe, Missouri.

WEAR-PLATE FOR SHOE-HEELS.

1,139,743.

Specification of Letters Patent. Patented May 18, 1915.

Application filed March 5, 1914. Serial No. 822,739.

To all whom it may concern:

Be it known that we, ALMOND J. WHITE and FREDERIC A. HAWLEY, citizens of the United States, residing at Chillicothe, in 5 the county of Livingston and State of Missouri, have invented certain new and useful Improvements in Wear-Plates for Shoe-Heels, of which the following is a specification.

10 This invention relates to new and useful improvements in metallic heel plates of the type which are secured to the rear edge of the shoe heel to prevent the wearer from running over the heel.

15 The principal object of my invention is to provide a wear plate which may be easily and quickly attached to any shoe heel with a minimum expenditure of time and labor, and will, when properly secured to the heel, 20 be firmly held against accidental displacement.

The above and additional objects are accomplished by such means as are illustrated in the accompanying drawings, described in 25 the following specification, and then more particularly pointed out in the claims, which are appended hereto and form a part of this application.

With reference to the drawings, wherein 30 there has been illustrated the preferred embodiment of this invention as it is reduced to practice, and throughout the several views of which similar reference numerals designate corresponding parts,

35 Figure 1 is a side elevation of a shoe, showing the preferred form of wear plate applied to the shoe heel; Fig. 2 is a detail perspective view of the preferred form of wear plate; Fig. 3 is a section on the line 2-2 of Fig. 2; Fig. 4 is a perspective view 40 illustrating the lower face of that heel tap which receives the upper portion of the wear plate; Fig. 5 is a perspective view of the bottom heel tap showing the grooves 45 which are formed therein to receive the base flange of the wear plate; Fig. 6 is a side elevation of a shoe, showing a modified form of the device in assembled position on the shoe heel; Fig. 7 is a perspective view 50 illustrating the modified form of wear plate in detail; Fig. 8 is a detail perspective view of the bottom heel tap; Fig. 9 is a perspective view illustrating that heel tap which receives the upper portion of the modified 55 form of wear plate; and Fig. 10 is a section

taken transversely through the heel upon the line 10-10 of Fig. 6.

The wear plate of the preferred form of the invention shown in Fig. 2, includes a semi-circular body plate 12, which is cut-away at its center portion, as at 13, providing a substantially semi-circular slot or opening. This opening is formed for the purpose of reducing the weight of the heel plate, and for cheapening the cost of manufacture by reducing the amount of metal employed. A number of apertures, indicated at 13', are cut in the body plate 12 to receive nails, studs or similar fastening devices, whereby the plate may be properly secured to the heel tap, indicated at 14 in Fig. 1. This heel tap 14, which is illustrated in detail in Fig. 4, is cut-away at its rear portion to receive the plate member 12. On the rear portion of the tap 14, there is 75 left a substantially semi-circular rib 15, which corresponds in shape to the opening of the slot 13, and is received therein when the plate member 12 is inserted between the heel tap 14 and the lower or bottom tap of 80 the heel, indicated at 16. This lowermost or bottom heel tap 16, which is illustrated particularly in Fig. 5, is provided with a recess, which, as indicated at 17, extends around the rear edge of the tap and is cut in from the 85 lower face thereof. The vertical walls 18 of this recess correspond in outline to the inner edge of a wear flange 19, which is formed on the body plate 12. This wear flange 19 is arranged in parallel spaced relation to the body plate 12, being connected thereto by a semi-circular flange 20 which extends at right angles to the plate 12 and is formed on the outer edge thereof, as best 90 shown in Fig. 2. The terminals of the flange 20 are beveled, as at 21, and are adapted to engage against the beveled shoulders 22 formed on the heel tap 16, as shown in Figs. 1 and 5. It will now be observed by referring to Fig. 5 that the semi-circular rib or 95 ledge 23, which is formed on the rear terminal of the heel tap 16 by cutting the tap away to produce the recess 17, is received within the semi-circular channel, which, as indicated at 24, is defined by the wear flange 19, connecting flange 20, and outer edge of 100 the body member 12.

Upon reference to Fig. 1, it will be noted that when the preferred form of wear plate has been properly attached to the heel of a 110

shoe, the wear flange 19 is flush with the lower face of the lower heel tap 16; that the body plate 12 is positioned between the lowermost tap 16 and the next adjacent tap 14, and that the connecting flange 20 forms a protecting rim for the rear edge of the heel. In other words, the connecting flange 20 and wear flange 19, which latter member is adapted to engage the ground and prevent running over of the leather heel tap, form in reality a semi-circular casing for the rear edge portion of the lower heel tap 16.

In the modified form of the invention shown in detail in Fig. 7, there is provided, as in the preferred embodiment of the invention, a semi-circular base plate or body plate, which is formed with a semi-circular opening 30. In the forward edge of the body plate are formed the wedge-shaped retaining lugs 31, which are adapted to be inserted in the heel tap 32, which is next adjacent the lowermost heel tap, indicated at 33. This heel tap 32 is, as shown best in Fig. 9, cut-away at its rear terminal, producing a semi-circular recess 34 and a transverse recess 35. By cutting away the heel tap in this manner, there is left a semi-circular portion 36 which is received within the opening 30 when the body plate of the device is positioned between the taps 32 and 33. The tap portion 36 being inserted in the opening 30, obviously assists the retaining studs 31 in holding the body plate against withdrawal from between the two lowermost heel taps.

Extending around the outer edge of the body plate of the modified form of the invention is a wear flange 37. This member 40 37, as best shown in Fig. 10, is substantially triangular in cross section, its outer face, indicated at 38, being arranged at right angles to the body plate, and its inner face, indicated at 39, being arranged at an approximate angle of forty-five degrees thereto. The lower face 40 of the wear flange 37 is thus relatively thick. The heel, when equipped with this modified form of the device, thus presents a metallic protecting band of considerable width to the ground. The lowermost heel tap, indicated at 33, is cut-away around the edge of its rear terminal to produce the beveled edge 43 and a beveled lateral shoulder 44. The beveled edge 43 of the lowermost tap is adapted to seat against the beveled face 39 of the wear flange 37, while the shoulder 44 is adapted to receive the diagonally cut terminals 45 of the flange 37.

60 Regarding the advantages presented by the particular construction of the modified form of the invention, it is to be noted that the flange 37 serves, not only to prevent the

heel from being run over, but also acts as a protecting casing for the rear edge of the 65 lowermost heel tap.

In reduction to practice, it has been found that the form of this invention illustrated in the drawings, and referred to in the above description as the preferred embodiment, is 70 the most efficient and practical; yet realizing that the conditions concurrent with the adoption of this device will necessarily vary, it is desirable to emphasize the fact that various minor changes in details of construction, 75 proportion and arrangement of parts may be resorted to, when required, without sacrificing any of the advantages of this invention, as defined in the appended claims.

What is claimed is:

1. A wear plate for shoe heels including a body plate, a wear flange, and a flange connecting the plate and wear flange, the second mentioned flange being substantially semi-circular in shape and having its terminals 85 inclined in a direction forwardly from the wear flange to the body plate.

2. A wear plate for shoe heels including a substantially semi-circular body plate having a substantially semi-circular opening, a flange depending from the body plate and having its terminals inclined in a direction forwardly toward the body plate, and a wear flange of substantially semi-circular shape extending laterally and inwardly from 95 the first mentioned flange.

3. The combination with a shoe heel having one tap cut-away at its rear portion to produce forwardly inclined shoulders, of a wear plate including a body portion arranged to engage against the upper face of the said tap, a flange depending from the body plate and embracing the cut-away portion of the tap, the terminals of said flange being inclined forwardly toward the body portion, whereby they may engage against the inclined shoulders of said tap, and a wear flange formed on the first mentioned flange and extending inwardly and laterally therefrom.

4. A wear plate for shoe heels including a body plate having a laterally enlarged wear surface and a flange portion connecting the wear surface and the body plate, said flange portion being substantially semi-circular in 115 shape and having its terminals inclined in a direction forwardly from the extremities of the wear surface to the extremities of the body plate.

In testimony whereof we affix our signatures in presence of two witnesses.

ALMOND J. WHITE. [L. s.]
FREDERIC A. HAWLEY.
